(57) **CLAIM**

The ornamental design for a pet shock training mat, as shown and described.

DESCRIPTION

FIG. 1 is a perspective view of a pet shock training mat showing my new design;

FIG. 2 is a right side view of the pet shock training mat thereof;

FIG. 3 is a left side view thereof;

FIG. 4 is a front elevational view thereof;

FIG. 5 is a back elevational view thereof;

FIG. 6 is a top plan view thereof;

FIG. 7 is a bottom plan view thereof;

FIG. 8 is an enlarged perspective view of a controller in portion 8 of FIG. 1 thereof;

FIG. 9 is an enlarged right side view of the controller in portion 8 of FIG. 1 thereof;

FIG. 10 is an enlarged left side view of the controller in portion 8 of FIG. 1 thereof;

FIG. 11 is an enlarged front elevational view of the controller in portion 8 of FIG. 1 thereof;

FIG. 12 is an enlarged back elevational view of the controller in portion 8 of FIG. 1 thereof; and,

FIG. 13 is an enlarged top plan view of the controller in portion 8 of FIG. 1 thereof.

The broken lines illustrate unclaimed features of the pet shock training mat as well as spotlighted magnified view areas and form no part of the design claim.

1 Claim, 13 Drawing Sheets
